Primary Examiner — Ian Simmons*Assistant Examiner* — Richelle G Shelton(74) *Attorney, Agent, or Firm* — Banner & Witcoff, Ltd.(57) **CLAIM**

The ornamental design for a display screen with graphical user interface, as shown and described.

DESCRIPTION

The FIGURE a front view of a display screen with graphical user interface showing the new design.

The broken line showing of the remainder of the graphical user interface and display screen is for environmental purposes only and forms no part of the claimed design. The difference in shading indicates a contrast of appearance.
